Carpets

UNITED STATES PATENT OFFICE.

GEORGE CURTIS WRIGHT, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 13,311, dated September 19, 1882.

Application filed August 11, 1882. Term of patent 33 years.

To all whom it may concern:

Be it known that I, GEORGE C. WRIGHT, of New York city, in the State of New York, have invented a new and original Design for Carpets, of which the following is a specification.

This invention relates to a new and original design for carpets and similar fabrics; and it consists in the novel grouping and configuration of figures, hereinafter more fully described.

10 The accompanying photograph illustrates a face view of a carpet having my new design. The background A is filled in with various irregularly shaped and disposed groups of small fan-like, arch-like, triangular and right lined figures, as shown. Upon this ground are scattered at irregular intervals various leaf-clusters of irregular shapes. The different clusters are made up of different kinds of leaves. The large cluster B is composed of 15 a central mass of oak-leaves with a group of acorns at the center, and smaller spraying leaves projecting outward on all sides. The cluster C is a drooping cluster of leaves of American ivy. The figure D is a cluster of 20 large leaves resembling maple-leaves. The figure E is a cluster of leaves resembling sassafras-leaves. The figure F is a cluster of leaves

resembling rose-leaves. Various other smaller clusters are scattered over the ground.

I claim—

1. The design for carpets, consisting of the ground A, substantially as shown. 30
2. The design for carpets, consisting of the cluster B, substantially as shown.
3. The design for carpets, consisting of the cluster C, substantially as shown. 35
4. The design for carpets, consisting of the cluster D, substantially as shown.
5. The design for carpets, consisting of the cluster E, substantially as shown. 40
6. The design for carpets, consisting of the cluster F, substantially as shown.
7. The design for carpets, consisting of the clusters B, C, D, E, and F, and the smaller clusters, substantially as shown. 45
8. The design for carpets, consisting of the clusters B, C, D, E, and F and the smaller clusters and the ground A, substantially as shown and described.

GEO. CURTIS WRIGHT.
